UNITED STATES PATENT OFFICE.

STOKELY D. WALTON, OF IMPERIAL, CALIFORNIA.

GANG DISK PLOW.

Application filed August 3, 1922. Serial No. 579,398.

To all whom it may concern:

Be it known that I, STOKELY D. WALTON, a citizen of the United States, residing at Imperial, in the county of Imperial and 5 State of California, have invented certain new and useful Improvements in Gang Disk Plows, of which the following is a specification.

This invention relates to gang disk plows, 10 and has for one of its objects to improve the construction and increase the efficiency and utility of devices of this character.

Another object of the invention is to provide a device of this character having means 15 whereby the disk carrying beam may be adjusted laterally to control the width of the combined furrows cut by the series of disks or cutters.

Another object of the invention is to provide a device of this character having a 20 simplified means for coupling the beam to the main axle and relatively adjusting the same.

Another object of the invention is to provide a device of this character having improved means for maintaining the cutting elements in lateral position.

With these and other objects in view the invention consists in certain novel features 30 of construction as hereinafter shown and described and then specifically pointed out in the claims, and in the drawings illustrative of the preferred embodiment of the invention:—

35 Figure 1 is a side elevation.

Fig. 2 is a plan view.

Fig. 3 is a front elevation.

Fig. 4 is an enlarged side elevation of the 40 adjustable brace members detached.

Fig. 5 is a sectional detail of one of the revolving disks.

Fig. 6 is an elevation of one of the disk clearing finger devices attached to the beam, the latter being in transverse section.

45 The improved device includes a main axle device 10 of any suitable construction and having vertical elongated bearings 11 at the ends, and slidably disposed respectively in the bearings are standards 12 and 12', the

50 standard 12' supporting a bearing wheel 13 in its forked lower end. The standard 12 is outturned at its lower end and terminates in an obliquely directed bearing for a guide wheel 13', the latter having an earth penetrating rib 13² and adapted to run in the

nearest furrow. The standards 12 and 12' extend for a considerable distance above the bearings 11 and are each provided with a collar 14 at the upper end, the latter held in any suitable manner, for instance by set 60 collars 15, to prevent longitudinal movement of the standards through the collars while leaving them free to rotate in the bearings.

Rigidly attached to each of the bearings 11 is an arm 16 having a toothed segment 17 at one end and extending at the other end forwardly of the bearings, and each coupled at its forwardly extending ends to the collars 14 by springs 18.

Pivoted at 19 to each of the forwardly extended portions of the arms 16 is an operating lever 20, each lever connected by a link 21 to one of the collars 14, and provided respectively with pawl devices 22 70 coacting with the teeth of the segments 17. By this means the standards 12 and 12' may be independently adjusted vertically through the bearings 11, and held in adjusted position by the coaction of the levers 20, and 75 their attachments, to control the vertical position of the wheels 13 and 13'.

Connected at 23 to the axle device 10 is one section 24 of a pull bar, while another section 25 is pivoted at 26 to the section 24. 80 A clevis device 27 is preferably coupled to the forward end of the section 25 to receive the draft appliance, not shown, but which may be a tractor, draft animals, or other power, as required.

Pivoted at 28 to the section 25 of the pull device is a rod 29, and rigidly connected at 30 to the standards 12 is a bar 31, the rod being pivotally coupled to the bar as shown at 32.

90 By this arrangement the standard 12 and its obliquely supported guide wheel 13' is so coupled to the swinging section 25, that any lateral movement of the draft appliance will rotate the standard 12 and cause the 100 wheel 13' to "trail" after the draft appliance, the freely rotating wheel 13' correspondingly "trailing" the draft appliance, as will be obvious.

Pivoted at 33 to the axle member 10 is a 105 relatively long heavy beam 34, the latter downturned at the rear end as shown at 35 and carrying a trailer wheel 36.

The member 34 is preferably formed of a 110 section of an I beam and provided with a

plurality of transverse apertures 37 at spaced intervals to receive clamping devices, such as U-bolts 38, whereby the standards 39 of cutting disks 40 are adjustably coupled 5 to the beam and adapted to be adjusted both vertically and rotatively. By providing a relatively large number of the apertures 37, the disk cutters may be supported at any required distance apart, or any required 10 number of the standards and disks employed, depending on the length of the beam and the number of the apertures 37.

For the purpose of illustration 4 sets of the apertures are shown to receive and support 15 4 of the standards, but any number may be employed as required. It will be noted that a surplus number of the holes are shown in the beam rearwardly of the rear cutting disk support, to show that an additional 20 number of the disk supports may be employed if required.

Attached at 41 to the beam 34 near each of the standards 39, is a clearer device for each of the disks 40 and comprising a plurality 25 of fingers or spaced rods 42, to prevent weeds, clods, and the like from being carried over the disks.

Hingedly united at 43 to the beam 34 near its rear end is a brace member 44, and hingedly united at 45 to the axle 10 is another 30 brace member 46.

The brace members overlap at their free ends, and are each provided with a plurality 35 of transverse apertures 47 to receive clamp bolts 48, to provide for adjustably coupling the brace members.

If the beam 34 be set to "trail" rearwardly of the axle 10, or at right angles thereto, the disks 40 will also "trail" one 40 behind the other, but by shortening the distance between the hinge connections 43 and 45 of the brace members 44 and 46 by adjusting the bolts 48 in the apertures 47, the beam 34 may be correspondingly adjusted to 45 operate at an angle to the axle 10, as shown in Fig. 2, and this angularity may be increased or decreased to any desired extent within the range of the apertures 47 and the 50 lengths of the brace members 44 and 46, as will be obvious.

By this means the "furrow" produced by the coaction of the series of disks may be increased or decreased as required.

It will be noted that the disks 40 are arranged to operate relatively near to a line parallel to the surface of the ground, and are relatively shallow, as shown in Fig. 5, and mounted to rotate freely on the standards 39. By this means the force required 55 to draw the disks through the ground is materially reduced while at the same time the action is more uniform.

With the disks arranged as shown and operating nearly flatwise to the ground, 60 weights are not required to hold the disks in

the ground, but on the contrary the guide wheels 13 and 36 are necessary to keep the disks from cutting too deep into the soil.

By arranging the forward guide wheels 13 to be independently adjusted vertically, 70 the device may be readily adapted for use on inclined or sloping surfaces.

With the relatively small amount of "dish" given to the disks, they will clear more readily and with materially reduced 75 "draft."

The preferred embodiment of the invention is disclosed in the drawings and set forth in the specification, but it will be understood that modifications within the scope of 80 the claimed invention may be made in the construction without departing from the principle of the invention or sacrificing any of its advantages.

Having thus described the invention, what 85 is claimed as new is:

1. An apparatus of the class described comprising an axle having bearing wheels and supported to swing relative thereto at the ends, a jointed pull bar rigidly connected by the rear portion to the axle, an arm connected to one of said wheel supports, a controlling rod pivoted respectively to the arm and to the forwardly directed portion of the pull bar, a beam member swinging at 90 its forward end relative to said axle and carrying a plurality of earth engaging cutting disks, and a brake device adjustably coupling said beam to said axle, whereby the angular position of the beam relative to 100 the axle may be controlled.

2. An apparatus of the class described comprising an axle having bearing wheels at the ends and to which a draft appliance is adapted to be coupled, a beam member swinging at its forward end relative to said axle, a plurality of standards directed forwardly at their lower portions, means for coupling said standards to said beam for rotative and longitudinal adjustment, and a cutting disk mounted for rotation upon each of the forwardly directed portions of the standards and operating in approximately parallel relation to the surface of the 105 ground.

3. An apparatus of the class described comprising an axle having bearing wheels at the ends and to which a draft appliance is adapted to be coupled, a beam member swinging at its forward end relative to said axle, a plurality of standards directed forwardly at their lower portions, means for coupling said standards to said beam for rotative and longitudinal adjustment, a cutting disk mounted for rotation upon each of the forwardly directed portions of the standards and operating in approximately parallel relation to the surface of the ground, and a brace device adjustably coupling said beam to said axle, whereby the angular position 110 115 120 125 130

of the beam relative to the axle may be controlled.

4. An apparatus of the class described comprising an axle having bearing wheels 5 at the ends and to which a draft appliance is adapted to be coupled, a beam member swinging at its forward end relative to said axle, a plurality of standards directed forwardly at their lower portions, means for 10 coupling said standards to said beam for rotative and longitudinal adjustment, a

cutting disk mounted for rotation upon each of the forwardly directed portions of the standards and operating in approximately parallel relation to the surface of the 15 ground, and a plurality of clearer devices attached to the beam and coacting respectively with the cutting disks.

In testimony whereof, I affix my signature hereto.

STOKELY D. WALTON.
